UNITED STATES PATENT OFFICE.

HERMANN M. SCHMEELK, OF ROCKAWAY BEACH, NEW YORK.

SAFETY BATHING APPARATUS.

SPECIFICATION forming part of Letters Patent No. 269,600, dated December 26, 1882.

Application filed August 9, 1882. (No model.)

To all whom it may concern:

Be it known that I, HERMANN M. SCHMEELK, of Rockaway Beach, in the township of Hempstead, in the county of Queens and State of New York, have invented certain Improvements in Safety Bathing Apparatus, of which the following is a specification.

The object of this invention is to provide a more efficient means of preserving life and insuring safety in beach-bathing than is afforded by the ordinary surf-line, and also to insure in such an apparatus an elasticity or resiliency which will enable the parts to resume their original positions after being bent or sprung by the weight or force of the bathers exerted upon them.

My said invention comprises certain novel combinations of parts whereby these advantages are secured, and whereby, furthermore, the apparatus may be very readily taken apart—as, for example, when desired at the end of the bathing season—and whereby, also, it can be very readily reconstructed or put together again when required for use.

Figure 1 is a perspective view representing an apparatus constructed according to my said invention, and Figs. 2 and 3 are detail sectional views illustrating certain parts of the said apparatus.

A A are vertical elastic or resilient posts formed of iron pipes driven into the sand to any requisite depth, the character of these pipes being such as to combine great strength and lightness with the property of yielding readily, within certain limits, to lateral strain, and again resuming their position when relieved from such strain. These posts A are arranged in two substantially parallel rows, the tops of the posts of one row being connected with those of the other by a cross-bar, a b. The posts, with their cross-bars, (instead of two cross-bars, a b, to each post, only one cross-bar may be used when preferred,) constitute a frame-work which is extended at any necessary distance from the beach and more or less parallel thereto—in other words, in about the situation which, in any given locality, the surf-line is usually placed. This frame-work possesses sufficient stability to resist the strain exerted upon it by the action of the bathers, as hereinafter explained, and at the same time

sufficient elasticity to resume its position when released from such strain, this being due to the construction of the posts of wrought or drawn pipes, as aforesaid, which secure a hold upon the sand into which they are driven different from that of ordinary posts, and which also possess a flexibility in proportion to their length and weight very much greater than that derived from the use of posts or piles of ordinary construction.

Placed upon each end of each of the cross-bars a is a sleeve, C, which holds snugly upon the cross-bar, in order that it may not slip longitudinally thereon. The upper part of each sleeve is constructed with a peculiar clamp, as follows: Two lugs, c, parallel with each other and having a space, d, between them, project upward from the ring in planes parallel with the length of the cross-bar a. In these lugs are two coincident slots, a', and one of said lugs, moreover, is constructed with a small ear or nut, b', through which is screwed a set-screw, c'. Placed in the lower part of the space d is a clamping-block, e, in the under side of which is a semicircular notch, d', which is coincident with a similar notch, e', formed in the bottom space, d. A wedge or key, D, is passed into and through the slot a' in such manner that when said key is driven inward it will force downward the clamping-block e to grip the cable placed in or between the coincident notches d' and e'.

E E are cables which are extended through the gripping devices, as just explained, and thereby firmly attached to the ends of the cross-bars a by the driving inward of the keys D, as just explained.

In order that the cables may themselves brace the frame-work composed of the posts A and their cross-pieces, one end of each cable is provided with an anchor, F. These anchors are preferably composed of bent pipe, and have each but a single hook and a single cross-piece, f, so that when the anchors are dug into sand they are partially or wholly filled with the sand itself, and take a much firmer grip thereon than would be possible if the ordinary anchor were used for such purpose. As concerns this peculiarly-constructed anchor, however, considered apart from its combination with the cable, the posts, and the clamping devices, I

propose to secure the same by separate and distinct Letters Patent, and therefore in this present application do not claim the anchor by itself. The opposite or shore end of the series 5 of posts A has attached to it a winding drum or roller, G, which may be actuated by a suitable crank, h. This drum G, previous to the driving in of the keys D, as hereinbefore explained, is operated to draw the cables E sufficiently taut for the purposes for which they are 10 designed, which done, the keys D are driven in.

Each of the cables E has at intervals along 15 its length branch ropes or safety-lines I, the outer ends of which swing free and clear, and 20 are designed to float or drift in the water, so as to be within easy access to the bathers and to afford a ready and convenient means by which the bathers may connect themselves to the cables E, these floating or drifting safety-lines I being much more easily reached and 25 grasped than is possible with the ordinary surf-line.

By the means aforesaid greatly-increased safety is insured to bathers and the probability 25 of accident is greatly diminished. At the end of the season, or at any other time when desired, the apparatus may be readily taken down and just as readily replaced on occasion, and the apparatus itself, from its flexible and yielding 30 character, combined with stability and strength, is extremely well adapted to resist the rough action of the surf upon it.

What I claim as my invention is—

1. A safety bathing apparatus comprising 35 as its essential features a series of vertical posts formed of wrought-metal tubes driven into the sand or beach-bottom, a cable or cables, E, extended along the upper ends of said posts, and life-lines I, attached at intervals along the said cable, the whole arranged for 40 use and operation substantially as and for the purpose herein set forth.

2. The sleeves C, provided with the slotted lugs a', clamping-block e, and key D, in combination with the cross-bars a, posts A, and 45 cable or cables E, all substantially as and for the purpose herein set forth.

3. The combination of an anchor, F, cable E, hollow resilient posts A, and clamping devices for connecting the cable to the post, all 50 substantially as and for the purpose herein set forth.

4. The combination of the drum or roller G, the hollow resilient posts A, cables E, cross-pieces a, and sleeves C, having the lugs a', 55 clamping-block e, and key D, all substantially as and for the purpose herein set forth.

HERMANN M. SCHMEEELK.
